[57] CLAIM

The ornamental design for a prophylactic device as shown, and described.

DESCRIPTION

FIG. 1 is an elevational view of a prophylactic device showing my new design;

FIG. 2 is a top plan view thereof;

FIG. 3 is a bottom plan view thereof;

FIG. 4 is an elevational view of a prophylactic device showing a second modified embodiment of my new design;

FIG. 5 is a top plan view of the design shown in FIG. 4; and

FIG. 6 is a bottom plan view of the design shown in FIG. 4.

FIG. 1

FIG. 2

FIG. 3

FIG. 4

FIG. 5

FIG. 6
